UNITED STATES PATENT OFFICE

2,355,329

CAPSULE MAKING METHOD AND MACHINE

Edward A. Ravenscroft, Glencoe, and Robert E. Jordan, Deerfield, Ill., assignors to Abbott Laboratories, North Chicago, Ill., a corporation of Illinois

Original application January 11, 1940, Serial No. 313,338. Divided and this application March 27, 1943, Serial No. 480,782

7 Claims. (Cl. 18—5)

This application is a division of our application Serial 313,338, filed January 11, 1940, for Capsule making machine, wherein claims were directed to the special form of capsule therein and herein shown and also to the method and machine for making such capsules.

Our invention relates to an improved method and apparatus or machine for making multiple-compartment, soft gelatin capsules such as are used in the pharmaceutical and drug industries for dispensing liquid medicaments of various types.

The principal objects of our invention in respect of the method and machine for making multiple-compartment capsules is the provision of a method and machine for making liquid filled, soft gelatin capsules; to provide such a method and machine for making such capsules of substantially uniform size and shape, and the provision of a method and machine for making such capsules automatically and at high speeds.

Other objects of our invention include the provision of an improved, automatically operable, capsule making machine, in accordance with the last mentioned principal object, which shall be capable of manufacturing multiple-compartment, liquid filled, soft gelatin capsules by the use of flat sheets or strips of gelatin, and which shall not only be simple and foolproof in construction but in addition shall be capable of continuous reliable operation over long periods of time with little or no supervision by the operator; the provision of an improved capsule making machine of this general type which can be readily cleaned and sterilized and which can be changed over, within a relatively short period of time and with little or no adjustment, from the manufacture of multiple-compartment capsules containing a particular combination of dissimilar medicaments to the manufacture of multiple-compartment capsules containing a differing combination of dissimilar medicaments; and generally, the provision of a novel type of soft gelatin capsule and apparatus for making the same.

One form of the multiple-compartment capsule of the present invention and the details of one type of apparatus which can be used for manufacturing compartments of this type are illustrated in the accompanying drawing, where-

in—

Figure 1 is a fragmentary view, partially in section, showing certain of the details of a capsule making machine which is operable to man-

ufacture two-compartment, soft gelatine capsules;

Figures 2, 3, and 4 are fragmentary sectional views, showing various steps in the formation of capsules by the use of the apparatus illustrated in Figure 1;

Figure 5 is a fragmentary perspective view of one form of nozzle mechanism which may be used in conjunction with the machine illustrated in Figures 1 through 4;

Figure 6 is a perspective view, partially in section, of one of the two-compartment, soft gelatine capsules manufactured by the apparatus illustrated in the other figures in the drawing; and

Figure 7 is a sectional view of the capsule illustrated in Figure 6.

The capsule making machine illustrated in the drawing is operable to manufacture soft gelatine capsules having two entirely separate, sealed compartments which may be filled with two dissimilar medicaments or other filling materials. The capsules may be spherical in shape, as illustrated at 11 in Figures 6 and 7, or they may 20 take the form of an ellipsoid, depending upon how much filling material is introduced into the two compartments 13 during the manufacturing operation. The two compartments 13 are separated by a common wall 15, and since this wall 15 is movable, within reasonable limits, relative to the outer wall of the capsule, the two compartments 13 can be made of substantially different capacity, an important feature when filling materials of certain types are used.

Reduced to its simplest elements, the capsule making machine illustrated in the drawing includes means for forming three relatively narrow, continuous sheets or strips 33 of gelatine; two flat-sided, wedge-shaped nozzles 11 arranged in close proximity to each other, as illustrated in Figure 5; means for simultaneously moving one of the gelatine sheets 33 between the two nozzles 11 and the other gelatine sheets 33 along the outer faces of the nozzles, whereby the two nozzles are sandwiched between the three sheets of gelatine; means actuatable to hold the two outer gelatine sheets 33 in contact with the nozzles 11 and the inner gelatine sheet 33 so as to form two coincident, expansible sacks, each of which connects with a nozzle outlet but is otherwise completely closed; a pump mechanism or the like for injecting a measured quantity of the liquid filling material into each of these sacks through the nozzle outlet with which it connects; annular cutter means actuatable to form

a capsule from each aligning pair of filled sacks by simultaneously cutting both sacks from the three strips of gelatine by an operation which seals the cut edges; and means for removing the finished capsule and the unused portion of the sheets from the machine. As will be made more apparent in the following detailed description of the apparatus, this mode of operation requires intermittent movement of some of the mechanical elements of the machine.

Except for the details and arrangement of the nozzles, the provision of means for forming three instead of two continuous sheets or strips of gelatine, and the provision of means for conducting three instead of two strips of gelatine into proximity with the nozzles, the capsule making machine of the present invention may be made substantially identical with the machine illustrated in U. S. Letters Patent 2,279,505, the application for which was filed on July 10, 1939, and which is assigned to the assignee of the present invention. For this reason, the accompanying drawing illustrates merely the details of the nozzles and the capsule making mechanism proper. It will be understood that the remaining elements of the machine are the same as the corresponding elements of the apparatus illustrated in Patent 2,279,505. The same reference numerals are used for the corresponding elements of the present machine as are used in Patent 2,279,505.

Each of the two nozzles 71 is wedge shaped at its lower end and may conveniently be made from a rectangularly shaped, relatively thin, metallic plate. The two nozzles 71 are supported side by side in close proximity to each other, preferably with the adjacent faces parallel as illustrated particularly in Figure 5. Any reasonable number of capsules can be made simultaneously by the capsule making machine of the present invention. The particular apparatus illustrated in the drawing is designed to make three capsules during each operation, and accordingly each of the nozzles 71 is provided with three symmetrically spaced, longitudinally extending, counterbored passageways 77 through which the filling liquid is conducted to the interior of the gelatine sacks formed at the outlet end thereof. For reasons which will hereinafter appear, the passageways 77 in the two nozzles are in substantial alignment with each other.

The slot-like passageway 78 formed between the two adjacent faces of the nozzles 71 is preferably of substantially the same thickness as the gelatine sheet 33 which is moved therethrough during the operation of the machine, and if desired the nozzle support may be made adjustable, so as to permit change in the width of this passageway. The upper or inlet end of each of the nozzle passageways 77 is connected to a suitable, intermittent feeding mechanism which may be similar to the piston type measuring pumps 79 illustrated in Patent 2,279,505. The measuring pumps should of course be arranged so as to permit convenient control of the amount of filling material which is forced into the gelatine sacks during each of the capsule making operations.

The three gelatine strips 33 are moved along the wedge-shaped ends of the nozzles 71 during the operation of the machine by means of power-driven squeeze rolls 113, which are supported a short distance below the nozzles by means of two short shafts 115. The shafts 115 are mechanically connected together by suitable gears, not shown, and are operated intermittently by a suitable mechanism which may be similar to that

used for operating the correspondingly numbered elements of the machine illustrated in Patent 2,279,505. The squeeze rolls 113 are provided with annular grooves 123 which align in the completed machine to form passageways through which the finished capsules can be removed. The engaging surfaces of the squeeze rolls 113 are preferably knurled in order to provide a better grip on the gelatine strips. Although the squeeze rolls 113 actually contact only the two outer strips of gelatine, no difficulty has been experienced in the accomplishing of simultaneous movement of the inner strip. The pressure provided by the opposed knurled surfaces of the squeeze rolls 113 accomplishes, in effect, a union of the three strips 33, and assures their simultaneous movement.

During the capsule forming and filling operations, the gelatine strips 33 must not be moved. This requirement makes it necessary that the squeeze rolls 113 and the feeding means for the gelatine strips shall be intermittently operated. Suitable mechanism for accomplishing this is illustrated in Patent 2,279,505.

The mechanism utilized to hold the two outer gelatine strips 33 in contact with the inner gelatine strip 33 so as to form two aligning, expandable sacks which connect with each adjacent pair of outlet openings in the nozzles 71, comprises two oppositely arranged sealing members 157, each of which is provided with a rectangularly shaped rear portion 159 adapted to engage a guide slot 161 formed in a suitable frame member 163. The guide slot 161 is normally closed by a removable plate 165, and the sealing members 157 are biased to the separated position by suitable springs 167.

Three uniformly spaced, cylindrical passageways 169 are formed in each of the sealing members 157. The passageways 169 align with each other when the sealing members 157 are in the engaged position of Figures 3 and 4, with the result that the two outer gelatine sheets 33 are held in contact with the inner gelatine sheet and with the adjacent surfaces of the nozzles 71 so as to form two circular sacks, each of which connects with the outlet end of one of the adjacent nozzle passageways 77. This is illustrated in Figures 3 and 4, and it will be apparent that the two outer gelatine sheets 33 can be expanded freely into the cylindrical cavity 171 (Fig. 3) formed by the aligning passageways 169.

The opposed surfaces of the sealing members 157 are cut away, as illustrated particularly in Figures 1 and 3, along an angle substantially equal to the angle formed between the outer faces of the two nozzles 71, in order to obtain a more satisfactory seal between the nozzles 71 and the gelatine sheets 33. Also, in order to prevent the nozzles 71 from projecting into the cylindrical cavity 171 within which the capsules are formed during the operation of the machine, the lower end portion of each of the nozzles 71 is provided with three semi-circular, cut-away sections 173 which align with each other and with the cylindrical passageways 169 when the sealing members 157 are in the engaged positions.

For the purpose of cutting away the filled sacks from the three gelatine strips 33 and thereby forming capsules during the operation of the machine, thin-walled, hollow, cylindrical cutters 175 are disposed for slidable movement within each of the cylindrical passageways 169 formed within the sealing member 157. Each of the three cutters 175 associated with each sealing

member 157 is attached at its inner end to a common operating member 177 (Fig. 1) having a rectangularly shaped rear portion 178 adapted to engage a guide slot 181 which, similarly to the guide slot 161 for the sealing members 157, is formed in the frame 163 and is normally closed by the cover plate 165. The cutter members 175 are biased to the retracted position of Figure 1 by means of springs 183, and in order to prevent the formed capsules from being drawn into the cylindrical passageways 169 in the sealing members 157 at the conclusion of the cutting operation, an ejector pin 185 is located centrally within in each of the passageways 169 in the cutter members 175. Each of the ejector pins 185 is permanently affixed at its rear end to the frame 163.

Proper sequential operation of the sealing and cutter members 157 and 175 is accomplished by the use of two pairs of cams 187 and 189 which are supported upon vertical cam shafts 191 journaled in suitable bearing supports, not shown, forming a part of the frame 163. Both of the vertical cam shafts 191 rotate at uniform speed, a suitable mechanism for accomplishing this being illustrated in Patent 2,279,505.

The first step in the capsule forming operation is illustrated in Figure 1. At this point the squeeze rolls 113 have been rotated to move the three gelatine strips 33 vertically downward a distance equal to about one and one-half times the diameter of the finished capsule. During this movement the sealing and cutting members 157 and 175 were held in the separated position.

At the conclusion of this forward movement of the gelatine strips 33 produced by the squeeze rolls 113, the two cams 189 which operate the cutter members 175 cause those members to move toward each other against the biasing action of the springs 183 from the position of Figure 1 to the position of Figure 2, in which latter position the opposed annular surfaces of the cutter members 175 are separated by a distance approximately equal to the combined thickness of the three gelatine sheets 33. The purpose of this movement of the cutter members 175 is to press the two outer sheets 33 into contact with the inner sheet 33 and thereby expel any air which might tend to become entrapped therebetween prior to the filling operation. Further rotation of the two vertical cam shafts 191 and the cams 187 cause the sealing members 157 to be moved from the separated position illustrated in Figure 1 to the sealing position illustrated in Figures 3 and 4. Simultaneously with this movement of the sealing members 157 to the sealing position, the cutter members 175 are retracted a distance somewhat greater than about one-half the diameter of the finished capsules as shown in Figure 3.

The opposing surfaces of the sealing members 157 press the gelatine sheets 33 into contact with each other and with the adjacent surfaces of the nozzles 71 in such manner that a circular area of each of the outer gelatine sheets is confined about each of the nozzle outlet openings. These confined areas define six separate, gelatine sacks, each of which connects with one of the nozzle outlet openings but is otherwise completely closed. Due to the fact that the passageways 169 in each of the sealing members 157 align when those members are in the sealing position, the outlines of the three sacks formed by the right-hand sealing member 157 exactly coincide with the outlines of the three sacks formed by the

left-hand sealing member 157, the confined portion of the central gelatine sheet 33 serving as a common wall for each pair of sacks.

Each of the sacks thus formed is individually capable of expanding into the cylindrical cavities 171 formed by the aligning passageways 169 when the filling liquid is pumped therein. The sealing members 157 should press firmly against the gelatine sheets 33 but should not engage the sheets too tightly, in order to obviate any possibility of cutting therethrough.

While the sealing members 157 are held in the engaged position of Figure 3, the capsule filling means is operated and a predetermined, measured quantity of the liquid filling material is forced into each of the six gelatine sacks whose outlines are defined by the opposed surfaces of the sealing members 157. As a result of this operation, each of the sacks is expanded to a substantially hemispherical form, as illustrated by the dotted lines in Figure 3. The two adjoining sacks formed at each of the pairs of outlet openings in the orifice mechanisms will be complementary in shape, due to the fact that the inner gelatine sheet 33 is common to each of the sacks in that pair.

Immediately following the formation of each of the complementary pairs of gelatine sacks, the control cams 189 for the cutter members cause those members to move from the partially separated position of Figure 3 to the position of Figure 4, in which latter position the opposed annular surfaces of the cutter members 175 engage with substantial pressure. The result of this engagement of the cutter members 175 is to cut out each of the aligning, complementary pairs of expanded sacks from the main body of the three sheets 33 and to simultaneously seal the edges of the resulting capsules, as illustrated at 11.

Immediately following the engagement of the cutter members 175, which marks the completion of the capsule forming operation, the cams 187 and 189 and the associated springs 167 and 183 which operate the sealing and cutter members 157 and 175 effect the movement of those members from the position of Figure 4 to the separated position of Figure 1. At this point, the squeeze rolls 113 are again operated to produce a downward movement of the three gelatine sheets 33, whereby the three capsules 11 just completed are moved from the position of Figure 4 to the position of Figure 1, at the same time new portions of the gelatine sheets 33 are presented for the machine to operate upon.

Under ordinary operating conditions, the capsule 11 will not be cut entirely free from the sheets 33 by the cutter members 175, and as a matter of fact, it is desirable that they shall not be completely cut away from those sheets, since a slight attachment of the capsules 11 to the sheets 33 will provide a convenient means for holding the capsules during their passage through the squeeze rolls 113, after which the capsules may be very readily removed from the gelatine sheets 33 by brushing or the like. The portion of the gelatine sheets 33 which remains after the capsules 11 have been removed therefrom constitutes what is known in the trade as a "net." The gelatine in the net may of course be reclaimed. To prevent the gelatine sheets 33 from sticking to any part of the apparatus it may be found necessary to apply mineral oil to various of the surfaces contacted by

the gelatine sheets. Suitable apparatus for accomplishing this is, of course, well known in the art.

It is not essential in all instances that the cutter members 175 be moved into the partially engaged position of Figure 2 as the first step in the operation of the machine. While this mode of operation is preferred, for the reason that it effects positive elimination of air from between the sheets of gelatine, any air so entrapped may be eliminated by other means, or, under certain circumstances, the amount entrapped may be so small as to be unobjectionable. If the Figure 2 step is eliminated, the only change in the operational sequence will be that the step of Figure 3 will follow immediately after the step of Figure 1.

The details of the multi-compartment capsule which is formed by the procedures described in the foregoing are illustrated in Figures 6 and 7, and as has been pointed out previously, the capsule is provided with two entirely separate compartments 13, each of which is sealed from the other. The capsule thus constitutes a true multiple-compartment capsule and may be used for the dispensing of two dissimilar or mutually reactive medicaments. The capsule satisfies a need which has existed in the industry for a long period of time, and yet at the same time it can be readily manufactured at high speed on automatic machinery, as described in the foregoing.

It will be apparent that the multiple-compartment capsules of the present invention can be filled not only with liquid but with pasty or semi-liquid substances. Accordingly, when the term "liquid" is used herein it is intended to include semi-liquid, pasty or plastic substances. Also, it is our desire that the accompanying claims shall be given the broadest possible construction consistent with the language appearing therein and the prior art.

We claim:

1. The method of continuously manufacturing two-compartment, liquid filled, soft gelatine capsules which consists in conducting three sheets of gelatine into proximity with a pair of nozzles in such manner that said nozzles are sandwiched between said sheets, confining predetermined areas of said sheets so as to form two expandible sacks having a common wall and which sacks are in substantial alignment with each other and each of which is open only to the outlet of one of said nozzles, expanding said sacks by forcing liquid filling material into said aligned sacks and thereby expanding said sacks, and then simultaneously severing both of said filled sacks from said gelatine sheets by an operation which simultaneously seals the edges of both sacks and unites those edges together so as to form a single capsule.

2. The method of continuously manufacturing two-compartment, liquid filled, soft gelatine capsules which consists in bringing three sheets of gelatine into proximity with each other, adjacent the outlet openings of two closely spaced nozzles, confining predetermined, aligning areas of the two outermost sheets so as to form two aligned, expandible sacks, both of which have one common wall and each of which is open only to the outlet of one of said nozzles, forcing filling material into said aligned sacks whereby each sack is expanded into a substantially hemispherical form, and then simultaneously severing both of said filled sacks from said sheets by an operation which simultaneously seals the edges of both

sacks and unites those edges together so as to form a single capsule.

3. In a machine of the class described, a pair of generally wedge-shaped nozzles arranged side by side, means for moving a sheet of gelatine between said nozzles and a sheet of gelatine along the outer face of each of said nozzles, whereby said nozzle members are in effect sandwiched between said sheets, sealing means operable to confine predetermined areas of said sheets so as to form two separate, complementary, expandible sacks, which are in substantial alignment with each other and each of which is open only to the outlet of one of said nozzles, said nozzles being operative to deliver a quantity of filling material into the respective sacks connected therewith, and cutter means operable to simultaneously sever both of said aligned sacks from said sheets and to simultaneously unite the edges of said sacks so as to form a two-compartment capsule.

4. In a machine of the class described, a pair of generally wedge-shaped nozzles arranged side by side, means for moving a sheet of gelatine between said nozzles and a sheet of gelatine along the outer face of each of said nozzles, whereby said nozzles are in effect sandwiched between said sheets, a pair of oppositely arranged sealing members each of which is provided with a centrally located passageway, means for moving said sealing members toward each other with said passageways in substantial alignment so as to hold together a predetermined area of said sheets and thereby form two separate, expandible sacks which are in substantial alignment with each other and each of which is open only to the outlet of one of said nozzles, said nozzles being operative to deliver a quantity of filling material into the respective sacks connected therewith, and tubular cutter members movable through said aligned passageways into engagement with each other to simultaneously sever both of said aligned sacks from said sheets and to simultaneously unite the edges of said sacks to form a two-compartment capsule.

5. In a machine of the class described, a pair of generally wedge-shaped nozzles arranged side by side, means for intermittently and simultaneously moving a sheet of gelatine between said nozzles and a sheet of gelatine along the outer face of each of said nozzles, whereby said nozzles are in effect sandwiched between said sheets, a pair of oppositely arranged, slidably supported, sealing members axially movable toward each other from a separated position to a sealing position, said sealing members being provided with aligning, cylindrical passageways which define a cylindrical cavity when said members are in the sealing position, means actuatable following each intermittent forward movement of said sheets to move said sealing members from the separated to the sealing position, in which latter position said sealing members confine a circular area of said sheets and thereby form two separate, expandible sacks which are in substantial alignment with each other and each of which is open only to the outlet of one of said nozzles, said nozzles being operative to deliver a quantity of filling material into the respective sacks connected therewith, tubular cutter members movable through said aligned passageways into engagement with each other to simultaneously sever both of said aligned sacks from said sheets and to simultaneously unite the edges of said sacks to form a two-compartment capsule, and means for moving said sealing members and said cutter

members to the separated position following each cutting operation.

6. In a machine of the class described, a pair of generally wedge-shaped nozzles arranged side by side, means for intermittently and simultaneously moving a sheet of gelatine between said nozzles and a sheet of gelatine along the outer face of each of said nozzles, whereby said nozzles are, in effect, sandwiched between said sheets, a pair of oppositely arranged sealing members axially movable toward each other from a separated position to a sealing position, said sealing members being provided with aligning, cylindrical passageways which define a cylindrical cavity when said members are in the sealing position, tubular cutter members movable through said aligning passageways from a separated position to an engaging position, means actuatable following each intermittent forward movement of said sheets to move said cutter members from the separated position into an intermediate position in which said cutter members press said sheets together with sufficient force to expel any air which may be entrapped therebetween, another means actuatable following each movement of said cutter members to said intermediate position to move said sealing members from the separated position to the sealing position in which said sealing members confine a circular area of said sheets and thereby form two separate, expandible sacks which are in substantial alignment with each other and each of which is open only to the outlet of one of said nozzles, retracting means operable following each movement of said sealing members to the sealing position to retract said cutting members a short distance, said nozzles being operative to deliver a quantity of filling material into the respective sacks connected therewith when said cutting members are so re-

tracted, said first mentioned means being actuatable following each filling operation to move said cutter members into engagement with each other, thereby simultaneously severing both of said 5 aligned sacks from said sheets and simultaneously uniting the edges of said sacks to form a two-compartment capsule, and means for moving said sealing members to the separated position following each cutting operation, said first mentioned 10 means and said retracting means being also operative to effect separation of said cutting members and return thereof to their initial, separated position.

7. In a machine of the class described, a pair 15 of generally wedge-shaped nozzles arranged side by side, each of said nozzle members being provided with a plurality of similarly spaced outlet openings, means for moving a sheet of gelatine between said nozzles and a sheet of gelatine along 20 the outer face of each of said nozzles, whereby said nozzles are in effect sandwiched between said sheets, sealing means operable to confine predetermined areas of said sheets so as to form a separate, expandible sack connecting with each 25 of said nozzle outlets, the sacks formed at each adjacent pair of outlet openings being in substantial alignment with each other and each of said sacks being open only to one nozzle outlet, said nozzles being operative to deliver a quantity 30 of filling material into the respective sacks connected with the outlet openings of said nozzles, and cutter means operable to simultaneously sever each aligned pair of filled sacks from said sheets and to simultaneously unite the edges of 35 each of said pairs of aligned sacks so as to form simultaneously a plurality of two-compartment capsules.
